UNITED STATES PATENT OFFICE

2,523,183

FABRIC TEARING MACHINE

Herbert W. Beall, Sumter, S. C., assignor to The
Springs Cotton Mills, Lancaster, S. C., a cor-
poration of South Carolina

Application July 11, 1946, Serial No. 682,910

1 Claim. (Cl. 164—84.5)

My invention relates to a machine for tearing off lengths of sheet material from a strip of material of indefinite length and it is an object of the invention to provide simple and effective means whereby pieces of predetermined length may be severed from a strip of indefinite length by a tearing operation.

A further object of the invention is to provide measuring means coupled with means for making an initial cut near one edge of the strip after measuring a predetermined length of the material, such as cloth, or the like.

Another object of the invention is to provide strip feeding means combined with pull-off means set into operation at a predetermined time and then moving faster than the feeding means for tearing off the predetermined length.

Other objects and advantages of the invention will appear upon consideration of the drawings, which are made a part of this application and in which similar reference characters indicate similar parts, and of the following description:

Figure 1 is an elevation of the machine of my invention, with parts omitted;

Figure 2, an elevation of parts of the machine, viewed from the left in Figure 1; and

Figure 3, a fragmentary plan view.

In the drawings, reference character 10 indicates a conventional source of supply of strip material, such as a roll of material suitably supported for rotation as the strip is drawn off. In the embodiment of the invention here illustrated, which is the form at present preferred by me, the strip 11 passes from the supply 10 about a guide roll 12, between a pair of feed rolls 13, and then about a measuring roll 14. At the side of the measuring roll remote from the point of first contact of the strip with the measuring roll there is located a rubber covered feed roll 15 which coacts with the measuring roll to feed the strips through the machine.

The measuring roll carries means for making an initial incision in the strip, here shown as comprising a radially movable cutting knife 16 mounted on a reciprocating bar 17 that is radially slidable on the measuring roll in a bearing 18 and which is normally forced inward by means of a spring 19. The knife 16 is pointed, as shown in Figure 2 and is so shaped as to be first pushed through the strip at a little distance from the side edge of the strip, after which it cuts its way through to the edge of the strip, due to the inclined sharp edge at one side of the knife as shown at 20.

The length of the piece to be torn off is gov-

erned by the circumference of the measuring roll. For operating the knife 16 at the appropriate time, a cam 21 is mounted in fixed position on a beam 22 forming part of the framework of the machine.

Immediately following the initial cutting mechanism above described, there is a clamp having an arm 23, the clamp being pivoted at 24 in a bearing on the measuring roll 14 and having an arm 25 projecting beyond a side face of the measuring roll. A cam 26 fixed to the beam 22 is located so as to engage the arm 25 and tilt the clamp about its pivot into engagement with the material on the measuring roll, so to clamp the material to the measuring roll. The clamp arm 23 will pass with the material between the periphery of the measuring roll and the feed roll 15 and serves to hold the material and assist in the tearing operation.

A compressible roll 27 e. g., a roll made of or covered with rubber is mounted in fixed bearings beyond the point at which the strip leaves the above described rolls and a coating roll 28 is mounted in bearings on a lever 29 which lever is pivoted at its lower end at 29' on a fixed support, the lever being normally moved by a spring 31 away from the compressible roll but being adapted to be moved toward said compressible roll by an eccentrically located cam 30 mounted on the measuring roll and adapted to engage with a roller 33 at the free end of lever 29. The mounting of the rolls 27 and 28 is such that they will engage first at the end where they act on that part of the strip which has been initially severed, as indicated at 32 in Figure 2. The rolls 27 and 28 may be conical in form, with their larger ends directed toward that side of the machine where the incision at 32 occurs. The roll 27 may be made of rubber, or otherwise made compressible.

In the operation of the machine, it will be seen that as a strip of cloth, oil cloth or the like is fed from the supply 10, it will pass about the measuring roll 14 until the primary severing device 16 makes an incision adjacent an edge of it due to action of the cam 21, after which the material will be drawn through the machine by the conjoint action of rolls 14 and 15. At about the time the incision passes between rolls 14 and 15 the clamp arm 23 is forced into clamping engagement with the material which is back of the primary incision and the pull-off rolls 27 and 28 are brought into engagement. The pull-off rolls may have non-parallel axes or they may be conical or in some other way may be arranged so that they grasp the edge of the material adjacent the pri-

mary incision and begin tearing at that side, the tearing operation progressing across the material until the length is completely severed, after which the operation may continue progressively and automatically, without any necessity for human intervention except to maintain the supply at 10.

The machine will also operate on folded or doubled material by making the initial cut in the folded edge and then tearing toward the two selvage edges. When I speak of an edge of material I mean the selvage edge of a single sheet of material or the folded edge of doubled material, both in the specification and in the claim.

It will be obvious to those skilled in that art that many variations may be made in the devices herein disclosed. For example, the knife may be replaced by other initial severing means, the operation of the pull-off rolls may be changed, the dimensions and arrangement of parts may be altered, and so on. Therefore I do not limit myself to what is shown in the drawings and described in the specification, but only as indicated in the appended claim.

Having thus described my invention, what I claim is:

A device for tearing lengths of material from

strips of cloth or the like, comprising means for holding a supply of strip material, a measuring roll, a feed roll coacting with the measuring roll at a point remote from the point of first engagement of the strip with the measuring roll, a cutter rotating with the measuring roll, means to cause said cutter to make an initial cut in an edge of the strip adjacent said point of first engagement with the measuring roll, pull-off rolls acting on the strip beyond the feed roll, means for clamping a portion of the strip behind the initial cut as said cut passes beyond the feed roll, and means for causing the pull-off rolls to grip the strip and tear the engaged portion from the remainder of the strip.
